UNITED STATES PATENT OFFICE.

CHARLES E. RENSHAW, OF EAST ORANGE, NEW JERSEY, ASSIGNOR TO NEWMAN CLOCK COMPANY, OF NEW YORK, N. Y., A CORPORATION OF NEW YORK.

CARRYING-POUCH FOR WATCHMEN'S TIME-REGISTERS.

1,179,758.

Specification of Letters Patent. Patented Apr. 18, 1916.

Application filed January 18, 1911. Serial No. 603,287.

To all whom it may concern:

Be it known that I, CHARLES E. RENSHAW, a citizen of the United States, residing at East Orange, county of Essex, 5 and State of New Jersey, have invented certain new and useful Improvements in Carrying-Pouches for Watchmen's Time-Registers, of which the following is a full, clear, and exact description.

10 This invention relates to watchmen's portable time-registers or clocks, and its chief object is to provide an improved pouch or carrying case for the clock, for the purpose of protecting the latter from 15 injury by the weather or other agencies while the watchman is on his rounds, as well as to make the clock more convenient to carry.

To these and other ends the invention 20 consists in the novel features of construction hereinafter described, and more particularly set forth in the appended claims.

Of the various embodiments of which the invention is capable I have selected for 25 illustration and specific description herein the one which at the present time is considered to exhibit the various features of the invention in their most convenient and effective form. This embodiment is illustrated in the accompanying drawings, in 30 which—

Figure 1 is a front view of the pouch, with the clock inside the same and with the front slide open to show the clock-face or dial. Fig. 2 is a bottom plan view of the body portion of the pouch, with the key-hole slide open. Fig. 3 is a section on line 3—3 of Fig. 4, looking in the direction of the arrows. Fig. 4 is a top plan view of the 40 pouch. Fig. 5 is a section on line 5—5 of Fig. 4.

The pouch is preferably made of leather, and comprises a body portion 10 and a removable cover portion 11 shaped to conform to the contour of the clock, 12, in the present instance cylindrical. The cover is provided with a central opening 13 to expose the clock face to view, which opening is covered by a suitable grille or lattice work 15 to protect the dial and the crystal over the same from mechanical injury. The precise construction of this grille is immaterial, but the form shown in the drawings will be found convenient and effective. This form consists of a metal

ring 14, in which a wire fabric 15 of large mesh is secured, as by riveting or soldering.

When the device is to be carried out of doors in stormy weather the clock should 60 also be protected from the elements, and for this purpose the cover is provided with a slide 16 by which the said opening can be tightly closed. The slide is mounted in parallel guides 17, 18, which are in turn 65 secured to a circular metal plate 19 fastened on the front of the cover and formed with a central opening to register with the aperture in the cover. On one end of the slide is a handle 20 by which 70 the slide can be actuated, and the other end has its edge concaved to expose the entire dial without withdrawing the slide entirely from its guides 17, 18.

Clocks of this type are actuated, for the 75 purpose of making the time record, by means of a suitable key inserted and turned in a key-hole which is usually on the bottom of the clock, as indicated in Fig. 2. The cover and body portions of 80 the pouch are therefore formed with registering apertures 21, 22, to expose the key-hole 23, thus permitting the watchman to insert and turn the key without taking the clock out of the pouch. Over the 85 aperture in the body portion is a plate 24 having an opening 25 registering with the aforesaid aperture, and at the sides of the plate are guides 26, 27, in which is a slide 28 by which the said opening may be 90 closed when desired, the slide being provided with an outwardly turned handle or finger piece 29 for convenient actuation. The other end of the slide is provided with 95 a deep notch 30, so as to expose the key-hole without pulling the slide entirely out of the guides. Detachment of the slide might result in accidental loss of the slide, particularly when the clock is carried about out of doors in the night, and to 100 prevent such detachment in the course of ordinary usage the edge of the notch 30 is provided with an inwardly extending finger 31 adapted to engage a short stud 32 on the plate 24 when the slide is drawn 105 out far enough to expose the key-hole. To permit the slide to be fully closed the notch therein is formed with a rather deep slot 33 to accommodate the stud when the slide is pushed in. When it is desired to 110

remove the slide entirely it may be done by springing the finger 31 over the stud.

The pouch is slung over the watchman's shoulder by means of a carrying strap 34, 5 passing through loops 35 fastened on the sides of the pouch cover, said loops being formed by straps 36, 37, the latter of which is also attached to the back of the pouch body so as to act as a hinge between said 10 body and the cover portion. The other strap, 36, is adapted to coöperate with a buckle 38 on the back of the pouch body, so as to secure the two parts of the pouch detachably together. The lower ends of the 15 carrying strap are attached to the ends of a strap 39 on which is mounted a leather piece 40. The key-hole apertures in the body and cover of the pouch being at the bottom and the carrying strap being freely movable in 20 the loops 35 it will be seen that although the apertures mentioned are normally covered by the leather piece they may be uncovered by grasping the loop 41, on the strap 39, and pulling the carrying strap through its guide 25 loops. When the clock is released after the key has been inserted and turned in the key-hole the weight of the clock carries it down against the cover piece 40. This insures the key-hole being closed after the registration 30 has been effected, even though the watchman should forget to close the slide 28. The cover 40 may be provided with a pad 42 of felt or other yielding material to cushion the descent of the clock and to insure 35 a close fit with the pouch cover. The inside of the front of the pouch cover may have a similar pad 43, to cushion the front of the clock against jars and shocks.

At the top the pouch body and cover are 40 provided with registering notches 44, 45, to accommodate the rings 46 on the top of the clock. These rings are used to attach a carrying strap when the clock is carried without being inclosed in a pouch, or when 45 it is desired to attach the strap directly to the clock with or without also connecting the strap to the pouch.

From the foregoing it will be seen that my 50 invention provides a convenient and effective carrying receptacle for the clock, effectively protecting the same against injury by accidental jars and shocks and from the elements in stormy weather. The construction 55 specifically described is of course merely the preferred embodiment of the invention, which can be embodied in other forms without departure from its proper spirit and scope as defined by the appended claims.

What I claim is:

80 1. A carrying pouch or case for a watchman's portable time-registering clock, comprising in combination, a body portion to receive the clock, a cover portion fitting the body portion and having means thereon to cushion the clock against jars, one of said

portions being provided with an opening to expose the clock face to view, a grille for said opening to protect the clock, and a sliding closure for said opening.

2. In a carrying pouch or case for a 70 watchman's portable time registering clock, in combination, a body portion to receive the clock, a cover portion fitting the body portion and having means thereon to cushion the front of the clock, one of said portions 75 having an aperture to expose the clock face, guides mounted on the apertured portion on opposite sides of the aperture, and a slide mounted in said guides.

3. The combination with a carrying pouch 80 or case, for a watchman's portable time-registering clock, having an opening for the insertion of an actuating key, of a removable cover for said opening, and a carrying strap 85 for the pouch, connected with the said cover whereby the weight of the pouch and contents when suspended by the carrying strap will cause the said cover to be seated over the key opening.

4. The combination with a carrying case 90 or pouch, for a watchman's portable time-registering clock, having in its bottom an opening for the insertion of an actuating key, of a carrying strap slidably connected with the pouch at the sides thereof, and a 95 removable cover for the key opening, connected to the ends of the carrying strap, whereby the weight of the pouch and contents when suspended by the carrying strap will cause the said cover to be seated over 100 the key-opening.

5. The combination with a carrying pouch or case, for a watchman's portable time-registering clock, having an opening for the insertion of an actuating key, of a sliding 105 closure for the opening, and means to prevent accidental detachment of the said closure from the pouch.

6. The combination with a carrying pouch or case, for a watchman's portable time-registering clock, having an opening for the insertion of an actuating key, of a removable closure for the opening to prevent dirt and the like entering the pouch and the clock through the opening and means independent 115 of the aforesaid closure to close said opening.

7. The combination with a watchman's portable time-registering clock, of a carrying case or pouch therefor having an opening to expose the clock face to view, and having an aperture for the insertion of an actuating key, a grille over the opening to protect the clock face when exposed to view, a removable closure for the opening to protect the clock from rain and the like, a removable closure for the key aperture to prevent the entrance of dirt and the like into the pouch and clock through said aperture, a cover for the aperture, and a carrying 125 130

strap attached to the cover and slidably connected with the pouch whereby the weight of the pouch and contents when suspended by the strap will cause the said cover to be seated over the key aperture.

8. In a carrying pouch for a watchman's time-registering clock, in combination, a body portion to receive the clock, a cover portion hinged to and telescoping over said body portion, said portion having openings

at the lower side thereof for the insertion of an actuating key into the clock, and a sliding closure for said opening located between the body and cover portions.

In testimony whereof I affix my signature ¹⁵ in the presence of two subscribing witnesses.

CHARLES E. RENSHAW.
